UNITED STATES PATENT OFFICE.

ARMAND MIEG, OF LEIPSIC, GERMANY.

PROJECTILE.

SPECIFICATION forming part of Letters Patent No. 463,528, dated November 17, 1891.

Application filed December 22, 1890. Serial No. 375,400. (No model.)

To all whom it may concern:

Be it known that I, ARMAND MIEG, a subject of the King of Bavaria, residing at Leipsic, in the Kingdom of Saxony, German Empire, have invented a certain new and useful Improvement in Projectiles and Cartridges, of which the following is a specification.

This invention has chiefly for its object to serve for firing short distances—as, for instance, for firing in drill. It may also serve for hunting, and generally in all cases where persons or other objects beyond the object aimed at are to be as little as possible exposed to danger by the projectile. The projectile is constructed with a short metallic shell of the same caliber as those destined for serious long range and penetrative firing, but is of but slight specific gravity. It is formed of two parts, the fore part and main body in one piece and a separately-formed bottom cap; but it may also be made of one single piece, or may consist of a metal shell or coating filled with a mass of little specific weight. In all cases the bottom or rear end of the projectile is made of a concave form, so that when the projectile is forced through the narrower grooves of the gun-barrel it may be easily compressed together. If the projectile is made of a coating filled with a light mass, as pasteboard, paper, wood, paper-pulp, &c., it will be necessary or convenient to have the filling material of a certain yieldingness, so as also to permit compression of the guiding coating part under the pressure of the lands and grooves when the projectile is passing through the barrel. Such projectile is provided in the center of its top or front with a bore of about 0.25 to 0.50 of a millimeter in diameter. This orifice reduces the weight and lessens the *vis viva* or momentum and catches the air, and thereby aids in reducing the velocity and contributes to shorten the range of the projectile. This bore also serves to make more stable the axis of rotation of the projectile and thereby lessen the pendulum vibration and increase the precision of firing within the short range for which my improvement is adapted. In projectiles consisting of a coating with a filling the bore may extend rearward near to the concave bottom, so as to form an axial canal for catching the air. To such projectile having a small weight, a

lessened velocity and an essentially-diminished *vis viva* is given by a diminished charge of powder in the cartridge-case. This lessens 55 yet more the momentum, the following arrangement being made in respect to the relative cartridge-case. The peculiarities of the entire construction reduce greatly the range and penetration of the shot. Cartridge-cases 60 which are in any manner spoiled in the manufacture and are unfit for long range or sharp firing, but otherwise are serviceable, are filled nearly up to the projectile with liquid plaster or with other liquid, or almost liquid, plastic, 65 and soon-stiffening material, which will on setting form a light but reasonably-firm filling. This filling, after its solidification and drying, is perforated lengthwise in the midst, or is in any other convenient way provided 70 with a priming-canal which is brought by branch holes into communication with the flash-holes in the rear or bottom of the cartridge-case. The projectile is not forced backward so far into the cartridge-case as to touch 75 the front surface of the filling mass. The parts are so formed and adjusted as to leave a space between the bottom of the projectile and the filling mass, which space holds the charge of powder, and therefore is so calculated 80 that the quantity of this charge corresponds to the weight of the projectile and to the range to be attained. The powder may, for attaining larger ranges, fill also the central priming-canal. Through limiting the 85 powder-room and powder of the cartridge according to the weight of the projectile, respectively, through a thereby diminished charge of powder, the object desired may be attained with certainty—that is, a projectile 90 striking with accuracy at a short range—but limited in its efficiency to a very short distance beyond the object aimed at, so that in shooting practice in the open air there will be little or no risk in entering or leaving the 95 ground or otherwise occasionally moving behind the target at a distance of about one hundred yards beyond, and consequently there will be no necessity to bar such grounds.

The accompanying drawings form a part of 100 this specification and show some examples of these projectiles. All are central longitudinal sections.

Similar letters of reference indicate corre-

sponding parts in all the figures where they appear.

Figure 1 shows a projectile consisting of a front part *a*, with a bottom cap *b* fitted over it, provided with a concave rear face *b'*. The parts *a* and *b* *b'* are stamped from copper or analogous metal or alloy and are forced together, and are through soldering, sweating, or other convenient way united strongly. The space between contains a light filling *c* of plaster or the like. A hole *c'* extends along the axis from the front nearly to the rear. This shows also the arrangement of the cartridge-case *d* with its cap *g* and the provisions for leading the fire therefrom to the front. The cartridge-case is largely filled with a mass *e*; but between the same and the projectile there remains a free space *f* for the charge of powder. This powder is in communication with the flash-holes at the rear of the cartridge-case by means of priming-canals *e'* and *e''*.

Fig. 2 shows a projectile having the bottom cap *b* with its cylindrical sides fitted within the front part or coating *a*.

Fig. 3 shows a projectile with a coating *a* and concave bottom *b'* made in one piece. This may be conveniently made by drawing first a cup with a close concave rear and an open front, corrugating the front and closing it together or nearly together by a concave die. Such treatment makes the front a little thicker and heavier than the other parts.

Fig. 4 shows a projectile consisting of coating *a* and filling *c*, the latter being molded with a concave bottom corresponding to *b'*. 35

Fig. 5 shows a projectile with a bore *a'* in the front, and Fig. 6 shows one having a filling *c* and a longitudinal canal *c'* in the filling. This is the projectile in Fig. 1 detached from the cartridge and also from the bottom cap. 40

I claim as my invention—

1. In a cartridge for drill practice, the long shell *d*, corresponding to the ordinary cartridge, inert filling *e*, passage *e'* to be filled with powder, and firing-cap *g* at the rear, in combination with a projectile comprised of two shells *a* and *b* *b'* and an inert filling *c*, arranged, as shown, so as to obtain a sufficient powder-chamber *f* between, all adapted for joint operation, as herein specified. 50

2. In a cartridge for drill practice, a projectile composed of a hollow metallic shell with a concave base *b'* and a supporting-filling *c*, of light material, having a central hole or bore *a'*, open at the front and closed at the rear, adapted to serve as herein specified. 55

In testimony whereof I have hereunto set my hand, at Leipsic, this 17th day of November, 1890, in the presence of two subscribing witnesses.

ARMAND MIEG.
